(57) **CLAIM**

The ornamental design for a display screen with graphical user interface, as shown and described.

DESCRIPTION

FIG. 1 is a front view of a display screen with graphical user interface showing a first embodiment according to claimed design; and,

FIG. 2 is a front view of a display screen with graphical user interface showing a second embodiment according to claimed design.

The outermost broken line illustrates the display screen and a boundary and the remaining broken lines illustrate portions of the graphical user interface. None of the broken lines form part of the claimed design.

1 Claim, 2 Drawing Sheets
